(57) **CLAIM**

The ornamental design for a hoe, as shown and described.

DESCRIPTION

FIG. 1 is a perspective view of a hoe showing my new design;
FIG. 2 is a front elevational view, thereof;
FIG. 3 is a rear elevational view, thereof;
FIG. 4 is a bottom plan view, thereof;
FIG. 5 is a top plan view, thereof; and,
FIG. 6 is a left side elevational view, thereof, it being understood that the right side elevational view is a mirror image thereof.

It is to be understood that any portion of any figure shown in broken lines are for environmental purposes only and form no part of the claimed design; and

It is to be understood that area of FIG. 3 shown inside a broken circle forms no part of the claimed design.
